UNITED STATES PATENT OFFICE.

STEVEN BIRO, OF WINDSOR, ONTARIO, CANADA.

DESIGN FOR A SAFETY HATPIN.

Application filed November 29, 1920. Serial No. 427,240. Term of patent 3½ years.

To all whom it may concern:

Be it known that I, STEVEN BIRO, a citizen of Hungary, residing at Windsor, in the Province of Ontario, Canada, have invented a new, original, and ornamental Design for a Safety Hatpin, of which the following is a specification, reference being had to the ac-

companying drawing, forming part thereof.

The figure is a front elevational view of a safety hatpin showing my new design.

I claim:

The ornamental design for a safety hatpin as shown.

STEVEN BIRO.
